UNITED STATES PATENT OFFICE.

SAMUEL CLELAND DAVIDSON, OF BELFAST, IRELAND.

EXPLOSIVE SHELL.

1,292,390.

Specification of Letters Patent.

Patented Jan. 21, 1919.

Application filed October 18, 1916. Serial No. 126,434.

To all whom it may concern:

Be it known that I, SAMUEL CLELAND DAVIDSON, of Sirocco Engineering Works, Belfast, Ireland, manufacturer, have invented certain new and useful Improvements in or Relating to Explosive Shells, of which the following is a specification.

This invention relates to ammunition adapted for short ranges, such as ordinarily 10 pertain to trench warfare, for example, up to ranges of about 500 yards or less.

With projectiles, shells or bombs made of cast iron, when filled with high explosive, such as ammonal, it is found that the projectiles 15 shell or bomb on bursting is practically blown into dust, or such small portions, that the shrapnel effect, due to the flying parts, is reduced to a minimum, the greater part of the destructive effect in such cases being 20 due to the shock of the explosion.

In the herein described ammunition, the projectile or shell has been designed to employ, as the explosive, ordinary gun-powder, or other explosive of moderate strength 25 (hereinafter included in the term "gun-powder") in contradistinction to high explosives, such as ammonal,—part of the objects of this invention being to insure that the fragmentation of the shell on bursting 30 shall be in pieces of such dimensions as will act with shrapnel-like effect.

To this end I employ a cast iron shell, the interior of which is constructed with internal projections so arranged that they are 35 comparatively weakly connected together by the outer surface of the shell, and the base of the shell is fitted with what (for brevity of description) is hereinafter referred to as the "fuse plug", which consists 40 of a disk-like collar with a central projection adapted to be screwed into a tapped hole in the base of the shell, and to centrally contain a time fuse inclosed within an open-ended metal fuse tube, one end of which is 45 projected into the interior of the shell, while the other end communicates with the cartridge case containing the propellant charge, and said cartridge case may be detachably connected to the base of the fuse plug in any 50 suitable way. The explosion of the propellant charge simultaneously projects said fuse plug and shell, and ignites the contiguous end of the fuse, leaving the car-

tridge case as a separate part in the gun, and, in order to prevent, or minimize any 55 risk of flash passing from the explosion of the propellant charge between the tube and the hole in the fuse plug through which the tube passes, the lower end of the tube is expanded into said hole, and likewise to prevent 60 any flash passing between the inclosing tube and the fuse itself, the upper end of the tube is crimped or corrugated in upon the insulated cover of the fuse itself. These 65 last mentioned features of the fuse tube are intended to be included under the above-mentioned term "fuse plug".

According to one modification of my invention, the cartridge case containing the propellant charge of powder, and which in 70 all the hereinafter described combinations is cylindrical in form, and of less diameter than that of the shell, is attached at its terminal end to the base of the fuse plug by means of an annular series of teeth or 75 prongs with gaps between them projecting from the base of the fuse plug, as shown at 9³, Figs. 1, 2, 2^a, 4 and 5, said series of prongs being arranged to fit tightly either within the inner or around the outer circumference of said cartridge case when same is pushed into close contact with the base of the fuse plug, whereby a close fitting but detachable connection between them is obtained, which upon explosion of the propellant charge immediately breaks said connection, and the cartridge case and fuse plug 80 separate which allows the gases from the explosion to pass into the air space between the outer circumference of the body of the 90 cartridge case, and the inner surface of the gun barrel, so that a predetermined average pressure over the entire base of the shell is therein created according to the 95 volumetric area of said air space, which can be made larger for a lower pressure, or smaller for a higher pressure, by increasing or diminishing the diameter of the body of the shell.

It is, however, desirable in some cases that 100 a portion of the gases should be allowed to escape into said exterior space around the cartridge case before the shell itself begins to move, and accordingly the gaps between the prongs of the fuse plug may be slightly 105 recessed into the base of the fuse plug, and

extended to the outer diameter of the cartridge, or the terminal end of the cartridge case may have slightly recessed gaps cut into it between its inner and outer circumference, and said recesses or gaps may in either case be filled with any suitable oleaginous substance, which will stand a fairly high temperature before melting, such, for example, as some compounds of paraffin wax, or hard soap, to prevent damp getting through to either the fuse or propellant charge within the cartridge case, and easily blow out from said gaps, which, (for brevity of description) I hereinafter term "premature escape vents",—the operative effect of which is to reduce the range for minimum throw of the shell to less than when said premature escape vents are not provided.

According to a second modification, the base of the fuse plug is attached to the terminal end of said cartridge case by means of an annular jointing sleeve, having its projecting end formed into several tooth-like prongs, with gaps between them, as shown at g^1 and g^2 in Figs. 6, 7, 8 and 9. The interior of this jointing sleeve is fitted with a lining of easily burst material, such as a paper tube of suitable length and thickness, which extends from the base of said sleeve to the bottom of the powder chamber in the cartridge case, as shown in Fig. 6, and the terminal end of the cartridge case projects within said prongs sufficiently to cover about one half the depth of the gaps between them, so that when said prongs are forced over the terminal end of the cartridge case, a firm but detachable connection of the cartridge case to the base plug is obtained, and on the explosion of the propellant charge, the paper lining bursts through the unprotected part of said gaps, which thus constitute "premature escape vents" as hereinbefore described.

Said paper tube may also alternatively be arranged so as to extend from the base of the fuse plug and within the annular series of said prongs, to a sufficient length to meet the terminal end of the cartridge case, as shown in Fig. 8, the diameter of the inner circle of the prongs being in this case less than in Fig. 6, but in other respects the operative action of this construction is similar to that described in reference to Fig. 6.

According to a third modification, the paper tubular lining of the cartridge case may extend from the base of the cartridge case up to, and abut against the terminal end of the prongs which project from the base of the fuse plug into and form a tight-fitting slip-joint connection with the end of the cartridge case, as shown in Fig. 10.

The cylindrical wall of the cartridge case has holes provided around it of suitable size, and in suitable position for the gases from the explosion of the propellant charge to

burst said paper tubular lining through these holes, which thus provide said "premature escape vents" for a portion of the gases into the air space around the exterior of the cartridge case, as already hereinbefore described in my first and second modifications.

Reference to the accompanying drawings, and the hereininafter contained description of same, will more fully elucidate the nature of my invention, and how it is carried into effect.

Figure 1 is a longitudinal section of the shell, fuse plug and cartridge case, according to my hereinbefore described first modification, with the end of the metal tube which projects into the shell, and contains the fuse, shown in elevation as crimped in upon the fuse itself, and the projecting teeth or prongs of the fuse plug shown as fitting into and forming a detachable connection with the inner circumference of the terminal end of the cartridge case.

Fig. 2 is an inverted plan of the fuse plug shown in Fig. 1 with four prongs projecting from the base of the fuse plug with gaps between them, said gaps being preferably slightly recessed into the fuse plug flange, so that when the terminal end of the cartridge case abuts against the non-recessed surface of said flange, a slight space is left between the terminal end of the cartridge case and the base of each recess, the depth of which may be varied to suit requirements, and may be filled with hard paraffin wax, or other suitable oleaginous and waterproof material, so that when the propellant charge explodes this material will be driven out, and provide said "premature escape vents" for a portion of the gases, as already referred to.

Fig. 2^a shows an alternative method for providing said "premature escape vents" by having suitable gaps cut into the terminal end of the cartridge case in lieu of having them recessed in the base of the fuse plug, as shown at g^4 .

Fig. 3 is a cross section on line A—B of Fig. 1.

Fig. 4 is a longitudinal section of fuse plug and cartridge case, showing a further arrangement of my hereinbefore described first modification, wherein the projecting teeth or prongs of the jointing sleeve are shown around the outer circumference of the terminal end of the cartridge case.

Fig. 5 is an inverted plan of the base of the fuse plug shown in Fig. 4, with four slotted out gaps between the prongs, but the number of these gaps and of the prongs may be varied as desired, and the gaps are preferably slightly recessed into the flange of the fuse plug to provide said "premature escape vents" for a portion of the gases as hereinbefore referred to.

Fig. 6 is a longitudinal section of the fuse

plug and cartridge case to illustrate the construction referred to in my hereinbefore second described modification.

Fig. 7 is an inverted plan of the fuse plug 5 shown in Fig. 6.

Fig. 8 is a longitudinal section of fuse plug and cartridge case, showing a further arrangement of the hereinbefore second described modification.

10 Fig. 9 is an inverted plan of the fuse plug shown in Fig. 8.

Fig. 10 is a longitudinal section of the fuse plug and cartridge case, to illustrate the construction referred to in my hereinbefore 15 third described modification.

The letters indicating the various component parts are the same in each figure, and are as follows:—

20 *a* is the cast iron body of the projectile or shell which is provided on the outer circumference with two machine turned parts marked *a'* which are of such diameter that they constitute a free sliding fit within the barrel of the gun. *b b* indicate a series

25 of longitudinal ridges within the shell of approximately triangular section with V-shaped depressions marked *c c* thus forming pyramid-like projections within the shell. The projections in one row are preferably

30 staggered with regard to those in the next row, and as shown in Fig. 3, which is a cross-section of the shell—the faces of the projections form a multi-pointed star. The shell itself is of the usual projectile shape

35 externally, and is provided with a nose orifice *d* adapted to permit of the explosive powder being filled into the interior of the shell,—the orifice being then closed with a screw plug *e*. *g* is the fuse plug which

40 screws into the base of the shell, having a collar-like flange at its base with an annular series of prongs, or a cylindrical jointing sleeve *g'* extending toward the cartridge case, with gaps *g²* slotted across so as to

45 form prongs *g³*. *g⁴*, Fig. 2^a, are slots cut across the terminal end of the cartridge instead of being recessed between the prongs into the base of the fuse plug *g*. *h* is a time fuse inclosed in a tube *h'* with the end of

50 the tube toward the cartridge case expanded or otherwise secured, so as to make a flash tight joint with the fuse plug *g*, and the inner length of the tube *h'* projects into the explosive powder contained within the body

55 of the shell *a* and the tube *h'* is so indented or corrugated into the insulating cover of the fuse itself, as to hold it firmly against the propulsive force of the propellant explosion, and prevent any flash passing be-

60 tween the fuse and inclosing tube directly to the explosive charge. The fuse itself is of suitable length to burn for the required number of seconds before reaching the explosive charge within the shell. *i* is a cartridge case containing the propellant charge

j. k is a wad, preferably made of sheet metal, on top of the propellant charge *j*, with a hole *k'* below which a thin paper wad is placed immediately on top of the powder, so that when the propellant charge explodes, 70 it bursts the paper through the hole in the metal wad, so that the flash can thus freely reach and ignite the base end of the time fuse. *l* is a paper tube fitted inside of jointing sleeve, and cartridge case, Fig. 6, and 75 inside of jointing sleeve only, Fig. 8. *l'*, Fig. 10, is an alternative arrangement of paper tube fitting inside of cartridge case *i*, and covering over the series of holes *i'* around the circumference of the cartridge 80 case *i*. *m* is a percussion cap in the base of the cartridge case for igniting the propellant charge. In use the explosion of the propellant charge *j* is effected by detonation of the percussion cap *m* in the base of the cartridge case *i*. 85

What I claim and desire to secure by Letters Patent is:—

1. In ammunition for guns adapted for use for short ranges in which ordinary gunpowder or other explosive of moderate strength can be employed for both propulsion and bursting charges, a projectile, a bursting charge disposed in said projectile, a fuse plug disposed in the base of the projectile, a fuse tube disposed in a hole in the fuse plug, a fuse in said fuse tube adapted to be lighted by the explosion of the propellant charge, a cartridge case of smaller diameter than the base of the projectile, 90 means for attaching the projectile to the cartridge case so that it can be readily detached, a firing charge disposed in the cartridge case, means for firing the firing charge, said fuse having a gas-tight connection with the sides of the fuse tube, whereby to prevent flash from the firing charge passing between the fuse and the fuse tube, said fuse tube having a gas-tight connection with the fuse plug whereby to prevent the said flash from passing between the fuse tube and the said fuse plug, and means for permitting the gases from the explosion of the propellant charge to escape into the annular space around the cartridge case as the projectile is forced away from the cartridge. 100 105 110 115

2. In ammunition for guns according to claim 1, the means for attaching the projectile to the cartridge case comprising an annular series of prongs having gaps between 120 the prongs adapted to provide premature escape vents.

3. Ammunition for guns according to claim 2, comprising means for closing the premature escape vents with a substance 125 which will be destroyed under predetermined conditions.

4. Ammunition for guns according to claim 1, the projectile having its interior constructed with internal pyramid-like pro- 130

jections arranged in circumferential rows staggered with regard to similar projections in both the circumferential and longitudinal adjacent rows.

5. Ammunition for guns according to claim 1 characterized by the projectile being of cast metal.

Copies of this patent may be obtained for five cents each, by addressing the "Commissioner of Patents, Washington, D. C."

In witness whereof, I have hereunto signed my name in the presence of two subscribing witnesses.

SAMUEL CLELAND DAVIDSON.
